United States Patent Office

Des. 233,598

Patented Nov. 12, 1974

233,598

RAZOR BLADE DISPENSER

Martin Glaberson, Stratford, Conn., assignor to Warner-Lambert Company, Morris Plains, N.J.

Filed Dec. 26, 1972, Ser. No. 318,073

Term of patent 14 years

Int. Cl. D9—03

U.S. Cl. D9—224

Fig. 1

Fig. 2

Fig. 3

Fig. 4

FIG. 1 is a top plan view of a razor blade dispenser showing my new design;

FIG. 2 is a side elevation view thereof;

FIG. 3 is an end elevation view thereof; and

FIG. 4 is a bottom plan view thereof.

The side view, not shown, is identical to that shown in FIG. 2, and the end view, not shown, is identical to that shown in FIG. 3.

I claim:

The ornamental design for a razor blade dispenser, as shown and described.
